(57) **CLAIM**

We claim the ornamental design and appearance of the finger tip scanner, as substantially shown and described.

DESCRIPTION

FIG. 1 is a front isometric view of a finger tip scanner;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a back isometric view thereof.
